Orange, N. J., a corporation of New Jersey

Application November 5, 1945, Serial No. 626,712

3 Claims. (Cl. 74—491)

1

This invention relates to phonographic machines and more particularly to those commonly known as dictating machines.

The dictating machine of the present invention embodies several interrelated improvements which make the machine more convenient to operate and to service.

In its basic structure, the present machine follows the conventional arrangement wherein a wax-like cylindrical record is supported for rotation and a carriage is advanced or fed along the said record. In such a carriage there is provided a mechanism or unit adapted selectively to engage the record for either recording sounds thereon or reproducing sounds therefrom. In the machine of the instant invention however, the unit mentioned above is one adapted to operate electrically, as distinguished from the more common type of acoustical device or unit.

It is an object of my invention to provide in a phonograph a separable link-connection of improved form between operating mechanisms in relatively stationary and movable portions of the phonograph cabinet so as to enable these mechanisms to be readily disconnected to permit opening of the cabinet for servicing and repair of the phonographic machine.

Other objects will appear from the following description and appended claims.

In said description, reference is had to the accompanying drawing, of which:

Fig. 1 is a plan view of the dictating machine of my invention;

Fig. 2 is a vertical section through the said machine, taken on line 2—2 of Fig. 1;

Fig. 3 is a vertical section, slightly enlarged, taken along line 3—3 of Fig. 1;

Fig. 4 is a section through the amplifier's controlling switch, as taken on line 4—4 of Fig. 5;

Fig. 5 is a section on line 5—5 of Fig. 4;

Fig. 6 is a fragmentary view, as seen along the line 6—6 of Fig. 3;

Fig. 7 is a horizontal section taken along line 7—7 of Fig. 2;

Fig. 8 is a side elevational view of a modified form of linkage, for the controlling switch of the amplifier shown in Fig. 3;

Fig. 9 is a front elevational view of the linkage of Fig. 8, and

Fig. 10 is a diagrammatical view showing the

2

arrangement of the several circuits forming the electrical system of my present dictating machine.

Referring particularly to Figs. 1 and 2, there will be seen a cabinet 1, closed at its top by a relatively heavy cast plate 2 adapted for the support of the operating mechanism of the machine. The top-plate 2 is hinged at 3 to the back of the cabinet, and it is supported at its front upon a bracket 4, to which it may be fastened by a thumb-screw 4' to prevent accidental dislocation and vibration of said plate. The bottom of the cabinet 1 is closed by a plate 1' having suitable openings 1'' (see Fig. 7) provided for ventilation in a manner hereinafter more fully described.

15 The top-plate 2 is provided with side standards 5 and 6 for supporting the cross-rod 7 and 8, and is further provided with an intermediate standard 9 for supporting a mandrel 10 which is used as a support for the cylindrical wax tablet 11. The record support 10 is conventional and its detail 20 of construction follows the disclosure of the Gramann Patent No. 2,010,717, issued August 6, 1935. During the operation of the machine, the support 10 is rotated by an axially aligned pulley

25 12 connected by a belt 13 to the motor M, which is suspended below the top plate 2 by a commonly known spring structure M', shown in Fig. 2. The rotation of the record support 10 is arranged to be controlled by the operator, and for this purpose the connection of the support 10 with the pulley 12 comprises a clutch mechanism 14 operated by a member 15 and a link 16 associated with an electro-magnet device 17. The device 17 is enclosed in a box as shown, and it is under control 30 of a hand-switch 18 on the mouthpiece or microphone 19 as hereinafter more fully pointed out.

A carriage 20 is mounted on rods 7 and 8 above the record tablet for movement thereacross. The carriage is moved by a feed-screw 21 mounted 35 parallel to the rods 7 and 8 on the standards 5 and 6. The feed-screw is turned in ratio with the mandrel, and for this purpose it is geared at 22 with a pinion 23 secured to the mandrel shaft 10'. The carriage is provided with a long sleeve 24, by means of which it is accurately supported and slid along the rod 7. On this sleeve within the hollowed portion of said carriage, there is mounted a camming block or member 25, see Figs. 1 and 3. This block is turned or moved in an arc about the 40 sleeve by a control lever 26; the movement being

45 50

effected by a link 27 connected to the lever at 26' and the block at 25'. The movement of the block 25 is to control the engagement or disengagement of the feed-nut 28 of the carriage with or from the feed-screw 21 and, moreover, to cause the rod 7 to be rocked in the sleeve and consequently in its journals 7' in the standards 5 and 6. For this last purpose, the cam block 25 has a key in the form of a set-screw 29 passing through a suitable arcuate slot made in the sleeve 24 and engaging a longitudinal key-way 31 made in the rod 7. The control lever 26 is also provided for simultaneously controlling the electrically operated unit 30 which is supported in the forward portion 21' of the carriage 20 and which is adapted for selective operation upon the surface of the record 11, such as for operation with a cutting tool for recordation, or operation with a pick-up stylus for reproduction. This unit need not essentially be of a specific construction in order to practice the present invention, however, for the present purpose, this unit is generally illustrated as being of the piezo-electric type and its specific construction need not be shown and described herein, as such a unit is fully disclosed in a co-pending joint application of the present inventor and Charles W. Dann, Serial No. 604,316, filed July 11, 1945, and having a common assignee with the present application.

An electro-acoustic recorder-reproducer unit, as here employed, requires the use of an electronic amplifier. The amplifier structure, which is generally indicated at 31, is located at the bottom of the cabinet portion 1. The structure first comprises a metallic receptacle or chassis 35, the solid bottom 35' of which is made to rest and be secured on the bottom plate 1', forward of the ventilating openings 1'' thereof, but with an insulating plate 36 between the said bottoms so that no electric contact is made therebetween. The electronic tubes 37 for the said amplifier are mounted to the rear wall of the chassis to extend rearwardly as shown; at a distance above but offset from the openings 1''. The necessary components and the wiring for the amplifier are provided within the receptacle 35, and leads thereof such as 38 and 39, are connected respectively to an on-and-off switch 40 and volume control unit 41, both of which have respective manual means 40' and 41' extending to the front of the cabinet 1 for control by an operator. Similarly, a pilot light 42 may be connected in the position shown to indicate the condition of the amplifier. Mounted directly on the right side 35a of the chassis 35 is an output-input controlling switch 43 for the amplifier 31, operable as hereinafter described by the control lever 26.

As the driving motor M and the amplifier 31 are both located beneath the top plate 2, considerable heat is generated in the cabinet 1. Accordingly, provision is taken to dissipate said heat to prevent the heavy plate 2 from getting hot to a point of generating hot-air currents thereabove and which would directly effect and lower the efficiency of the wax cylinder 11. To this end, an air-blower 45, supported at 46 to the motor M and driven thereby through a belt 47, is provided so as to draw air from the openings 1'' into the cabinet, then direct the air outwardly through the louvers 48 provided into the rear of the cabinet as shown in Figs. 2 and 7. The details of the ventilating system need not be described in total here, it being sufficient for the present purpose to state that such a system employs a metallic partition such as 50 in the pres-

ent drawing, to protect the amplifier and to serve as a baffle in the ventilating system. Partition 50 is directly secured to the metallic chassis 35 and it extends rearwardly but does not contact with the rear wall of the cabinet 1. It is detachably held to the chassis by the screws 51, and it is adapted to support along its rear a dished plate 52 serving as a drip pan for the motor M. The dished plate 52 has a downwardly bent portion 52' which however is adapted to touch or contact the rear wall of the cabinet 1. Advantage is made of this particular structure to form an electric capacitor (indicated as 53 in the diagram of Fig. 10) between the metallic body or cabinet 1 of the machine on one side and that of the amplifier chassis 35 on the other side. The capacitor 53 is of course predetermined in value when the assembly, comprising the cover plate 50 and pan 52, is in manufacture. For this purpose, an insulating sheet 54, of a chosen thickness, is placed between 50 and 52 and these parts are held firmly together by insulated screws 50'. In determining the value of the capacitor 53, attention is given to the thickness of the insulating pad 36 used between the metallic bottom 35' of the chassis and the metallic bottom 1' of the cabinet, as here too an electric capacitor may be formed. I make the pad 36 of a considerable thickness so that a very small capacity is created between the two bottoms 1' and 35' and this small value is then taken as a factor in determining the capacitor 53. The bottom 35' of the amplifier is held to the bottom 1' by means of suitable insulated screws not necessary here to show.

From the above, it will be understood that the chassis 35 of the amplifier is not grounded or in direct electrical contact with the cabinet 1 of the machine. Accordingly, viewing Fig. 10, it will be seen that the circuit, indicated as 58, for the combined recorder-reproducer unit 30 is not grounded or in electric connection with either the chassis 35 or cabinet 1. The unit 30 has a frame which is insulatedly mounted in the carriage 20 as is shown and described in the co-pending joint application mentioned above, and the circuit 58 therefor has a lead 58a which is directly connected to the "B—" of the amplifier as here shown. The other lead 58b of said circuit is connectable by the abovementioned switch 43 with the amplifier, either at the input or output thereof according to the position of said switch as hereinafter explained. In a similar manner, the microphone 19 has a circuit 59 of which one lead 59a is connected to the "B—" of the amplifier, and another lead 59b is connectable by the switch 43 either to the input or output of the amplifier, as determined by the position of the switch 43. Preferably, the leads 58a and 59a respectively comprise the metallic braided portions of the ordinary form of the shielded cables respectively used for the corresponding higher potential leads or wires 58b and 59b. Also, in the present instance the said metallic braided portions of said cables are covered with insulation so that they are prevented from making electrical contact with the chassis of the amplifier and cabinet of the machine.

The switch 43, through which the leads 58b and 59b are connected, is a rotary shielded unit whose outer metallic casing is at "B—" potential. It is mounted insulatedly on the chassis 35 by means of a Bakelite pad 32 and the insulated screws 33. This switch is preferably of the type 75 described and claimed in the Dann Patent No.

2,280,143 issued April 21, 1942 and having a common assignee with the present application. The casing of the switch 43 is composed of two circular portions 60 and 61. The portion 60 is held stationary onto the wall 35a by the screws 33 and it has a projecting central portion in the form of a hub 62 onto which the portion 61 is mounted for rotation. A large headed screw 63 holds the parts together as shown in Fig. 5. The portion 60 carries a plurality of terminals 65, 66, 67, 68, 69 and 70, all imbedded in suitable cylindrical insulating elements press-fitted into the base of said portion 60, and said terminals are extended outwardly as shown to provide means for soldering the leads which are to be connected to the switch. The portion 61 has transverse metallic walls 61a forming two distinctive shielded compartments 71 and 72, into which are mounted respective resilient contact members 73 and 74 adapted to bridge across the heads of the several terminals in the portion 60. In this respect, the contact member 73 is adapted to bridge across and form a circuit between the terminals 66 and 65, or it may, according to the position of the switch, form a circuit between 66 and the terminal 67. Similarly the contact member 74 is adapted to form a circuit by bridging across the terminals 68 and 69, or it may form a circuit between 69 and 70. It will be clear from Fig. 10 that the terminals 65, 66 and 67 are related to the high potential lead 59b of the circuit 59 for the microphone 19, and that the terminals 68, 69 and 70 are related to the high potential lead 58b of the circuit 58 for the combined recorder and reproducer 30. Accordingly, as the portion 61 of the switch 43 is turned with the bridging portions 73 and 74 thereof engaging their respective groups of terminals, the leads 58b and 59b will be alternately changed from input to output or vice versa, to place the microphone 19 in the input side of the amplifier and the unit 30 in the output side, or to place the microphone in the output side and the said unit in the input. In this last position of the switch, the microphone 19 is used as a loud speaker.

In order that the lead wires of the electric system may be as short as possible, the controlling switch 43 is mounted directly on the amplifier as explained. However, in order to control said switch as an incident of moving the control lever 26, a special means is provided by my invention to connect said lever with the switch and yet preserve the hinging feature of the top plate 2 so that it may be moved about its hinge 3 without interference from such a connection. For this purpose, there is mounted onto the rod 7 an arm 80, which is held fast to the rod by a screw 81 and which has a pivotal connection at 82 with a member 83. The member 83 has an upper extension 84 pivoted at 85 to a vertical section 86 of a separable link-connection generally indicated as 90. To adjust the section 86 relative to the angular position of the arm 80 on the rod 7, the member 83 has a downwardly extending portion 87 provided with an eccentrically disposed arcuate slot 88 engaging a stud screw 89 on the member 86. Movement of the member 83 about its pivot 82 will cause the slot 88 slightly to raise or lower the link member 83, and the stud screw may be tightened to preserve the adjustment. The link section 86 passes through a slot 90' in the top plate 2 and carries at its lower end a V-shaped spool 91 adapted to engage the bifurcated upper end of a lower link section 92. The section 92 is held in a vertical position by a

bracket 93 welded to the cabinet at 94. The bracket has a face 95 against which the section 92 rests, and a pair of spacers 96 cooperating with a cross-plate 97 to form a guide-way 98 (Fig. 7) for the vertical movement of the said section; there being an allowance for a slight play of the section 92 in the guide-way 98. The link section 92 is urged upwardly by a spring 99, stretched between the plate 97 and an extension 100 at the lower end of said section. A stop lug 101 is adapted to abut against a set screw 102 threaded in the plate 97 so as to define the limit of upward movement of the section 92. The extension 100 is pivotally connected at 103 to an arm 104 on the switch 43; the arm being of an insulating material so as to preserve the identity between ground and "B—" potentials and being secured to the switch portion 61.

With the parts of the connection 90 thus described, it will be clear that the switch portion 61 will be in its most clockwise position when the arm 80 is in its uppermost position and the control lever 26 is in its lowermost or recording position, as is seen in Fig. 3. Accordingly, in this position of the switch, the members 73 and 74 thereof respectively bridge between contacts 66 and 67, and contacts 69 and 70. This causes the microphone 19 to become connected to the input of the amplifier and the combined unit 30 to be connected with the output of said amplifier. Reversely, if the control lever be moved to its uppermost or reproducing position to cause the rod 7 to rotate and swing the arm 80 down to its lowermost position, then the link connection 90 will be operated to hold the switch in its most counterclockwise position to cause the bridging members 73 and 74 thereof respectively to bridge across the contacts 65 and 66, and 68 and 69. The unit 30 is thereby placed in the input side and the microphone in the output side of the amplifier so as to function as a speaker. As described, the link mechanism 90 lends itself quickly to separation as the top plate 2 is raised about its hinge 3; the link becoming automatically reunited as the plate is again lowered.

In Figures 8 and 9, there is shown another form of separable link connection, according to my invention, for the control of the switch 43. In this showing the rod 7 carries an arm 110 connected by a link 111, to a lever 112 pivoted on the rod 8. The lever is composed of two spaced-apart plates 112a and 112b, and it is apertured through both the forward portions of said plates so as to form a socket 113 for receiving a hardened ball 114 carried at the upper end of a link 115, whose bottom end 115' is connected to the aforementioned arm 104 of the switch 43. With this mechanism, the top plate may also be raised freely. However, during its upward movement, the arm 104 will follow only until it has reached its most clockwise position and thereafter the ball 114 will be forcefully disconnected from the socket 113. In reestablishing the connection, it is necessary to hold the link 115 up by means of a tool, such as a screw driver, engaging a notch 116, and forcefully reengage the ball with the socket by pressing upon the forward portion of the lever 112. The link 115 is normally held in a vertical position by a bracket 117 having a guide way 118 as shown.

As is customary, the control lever 26 is adapted to be moved to and held in a mid position where it establishes a condition of inoperativeness of the combined unit 30. With either of the link mechanisms described above the switch 43 is

rendered ineffective when the lever is so moved, as both the elements 13 and 14 of the switch are then in positions between their respective sets of contacts 65, 66, 67, and 68, 69, 70, and the associated circuits 58 and 59 will be accordingly opened.

In the present machine, a marked improvement of quality of recordation and of reproduction is achieved by placing in the circuits 58 and 59 respective filters, such as indicated at 120 and 121 in Fig. 10. The filter 120 is automatically placed in circuit by the switch 43 as said switch is operated to place the recorder stylus of the combined unit in the output side of the amplifier; and the filter 121 is in turn automatically placed in circuit when the microphone is alternately selected for the output of the amplifier so as to serve as a speaker. Accordingly, filter 120 which is a high-pass filter, as designated, serves to discriminate against the band of lower sound frequencies which are passed through the amplifier, and, in effect, to accentuate the band of the higher sound frequencies so that their recordation on the tablet 11 will be more prevalent; and the filter 121 which is a low-pass filter, as designated, serves to reverse this order during play back as the action of this filter reduces the ratio of the high to the low frequencies back to normal, i. e., as they were in the original voice, but in addition it acts to reduce the high frequency record scratch. As this scratch was not accentuated during recording the net effect of the two-filter system is to give a high quality of play back with a high ratio of desired signal to record surface noise, i. e. scratch.

While I have chosen to show a circuit arrangement wherein the filters 120 and 121 are alternately connected with the output of the amplifier, as an incident to the operation of the selective switch 43 for connecting the units 19 and 30 with the amplifier for either recording or reproducing, it will be understood that said filters may be so connected with the input of said amplifier, if desired. For instance, the filter 121 could be connected between the junction 58' and the input terminal 65, and the filter 120 connected between the junction 59' and the input terminal 67. In such case the terminals 68 and 70 associated with the output would have direct connections with the units 19 and 30 respectively. Moreover, if it were desirable, either one of the two filters could be arranged for connection with the input side and the other filter with the output side while still using the same switch 43. This would be done by connecting one filter between terminal 67 and the input, and the other filter between terminal 65 and the output, and also by connecting terminals 66 and 69 respectively with the appropriate ones of the units 19 and 30. The terminals 68 and 70 would then be connected respectively to input and output. In this case, the "B—" terminal would again complete the circuit for both the units 19 and 30. My primary object is to automatically introduce a band pass filter in the amplifier circuit during recording and another band pass filter in said circuit during reproducing.

In Figure 10, it will be seen that the aforementioned switch 40 is used as a master switch in the current supply circuit established by the plug-in cable 123, and that a second switch, such as the usual hook-switch 124, is used to control the motor circuit 125. In this last circuit there is used a resistance 126 which is in series with

the motor M as shown. This resistance is divided at any desired intermediate point, for instance as at 126', and a circuit 127 comprising a switch 128 is established in a manner to provide shortening of the resistance by closing said switch 128. When the motor M is to be used in connection with a source of high current supply or D. C. current, the switch is kept opened so that the resistance 126 will be fully effective to reduce the current. On the other hand, if a comparatively lower source of current supply or A. C. current is connected to the motor, the switch 128 is closed so that only a portion of the resistance will be effective to cause the motor to operate at a more efficient rate. Accordingly, A. C. and D. C. currents and/or different values of current may be used and appropriately controlled by this arrangement.

No fear need be entertained as to the possibility of the present machine producing electrical shock to the user. This is because the cabinet has no direct connection with the wiring system or with the potential of the cable 123. Accordingly, the machine may be set anywhere, even upon a metallic surface directly connected to earth, without ill effect. This is exemplified at 139 in the drawing. To provide proper ground return for the efficient working of the amplifier, a condenser 131 is connected between the "B—" terminal and the chassis 35, as seen in Fig. 10. This condenser may have an approximate capacity of .250 mf., and the capacity formed by the plates 50 and 52 may approximate 0.0025 mf.

For convenience of use of the present machine, there is provided a plug-in receptacle 133 at the back of the cabinet 1 as shown. To the right-hand side of the cabinet there is provided another convenient connecting means 134, which latter is used for the attachment or detachment of the microphone, as is shown in Figs. 1 and 3.

I claim:

1. In a phonograph: the combination of a cabinet having a stationary base portion and a movable cover portion mounted on said base portion for movement into open and closed positions; a selector device in said base portion for controlling the condition of the phonograph; a reciprocable hand control mounted on said cover portion for movement relative thereto and adapted for operating said selector device; and a separable coupling between said hand control and said selector device comprising first and second links coupled respectively to said hand control and said selector device and carried permanently with said cover and base portions respectively, mountings on said cover and base portions for said first and second links respectively for guiding said first link into releasable engagement with said second link as said cover portion is closed, and spring means associated with one of said links for yieldably maintaining the same in operative engagement with the other of said links within the range of back-and-forth actuation of said first link by said hand control while said cover portion is closed.

2. The combination set forth in claim 1 wherein said links are guided into abutment with one another as said cover portion is closed, and wherein said spring means urges said second link in opposition to its direction of actuation by said first link with force sufficient to maintain operative engagement between the links throughout the range of actuation of the first link by said hand control.

3. The combination set forth in claim 1 including a ball associated with one of said links and an arm carried with the other of said links and spaced a distance therefrom less than the diameter of said ball, said arm and other link being yieldable in directions towards and from each other and having aligned apertures for receiving said ball and for operatively interconnecting the links upon forcement of said ball between said arm and other link into said 10 apertures.
